PHASE STABLE AMPLIFIER

Allan C. Schell, Lexington, Mass., assignor to the United States of America as represented by the Secretary of the Air Force

Filed Sept. 3, 1958, Ser. No. 758,868

2 Claims. (Cl. 330—107)

(Granted under Title 35, U.S. Code (1952), sec. 266)

The invention described herein may be manufactured and used by or for the United States Government for governmental purposes without payment to me of any royalty thereon.

This invention relates generally to amplifiers and more particularly to a high frequency phase stable amplifier system having a negligible phase difference between its input and output.

Prior art devices have utilized amplifiers having expensive, complicated tuned networks; however, since at high frequencies tube capacity is a function of the signal level, a fairly large phase difference is found to exist between the amplifier inputs and outputs. The device of my invention utilizes a system comprising an amplifier, which may have a provision for 180° phase change, in conjunction with a phase sensing device and a phase correcting device, which are capable of operation at high frequencies, thus resulting in a device with a negligible phase shift between the input and system output.

Accordingly, it is an object of my invention to produce a novel phase stable amplifier system.

It is another object of my invention to produce an amplifier system having inherent phase stability comprising an amplifier, a phase sensing device and a phase correcting device.

It is still another object of this invention to produce a novel phase stable amplifier which utilizes conventional, currently available components, is economical to construct, and lends itself to standard mass production techniques.

It is a further object of this invention to produce a phase stable amplifier capable of accurate control of phase at high operating frequencies.

It is a still further object of the invention to produce a novel phase shifter capable of creating a 180° phase shift to an input signal.

It is another object of this invention to produce a novel phase corrector.

These and other advantages, features and objects of the invention will become more apparent from the following description taken in connection with the illustrative embodiments in the accompanying drawings, wherein:

Figure 1 is a block diagram of the system of my invention;

Figure 2 is a schematic diagram of the system of Figure 1; and

Figure 3 is a schematic diagram of an alternative embodiment of the system of Figure 1.

The system of my invention, as shown in Figure 1, utilizes an amplifier 10 and a feedback network comprising a phase sensing device 11 and a phase correcting device 12. The input and output signals are fed to the phase sensing device and compared. A difference in phase results in an error signal being applied to the phase corrector for adjustment of the amplifier.

Referring to Figure 2, the amplifier section receives a signal at the input through a coupling condenser C₁ to a dual triode V_{1a}—V_{1b} which in this embodiment gives

2

either a 0° or 180° phase shift to the incoming signal. A standard amplifier may be used in place of V₁; however, for use with the "Amplitude Scanning" system defined in application Serial No. 758,869, filed September 3, 1958, to Carlyle J. Sletten, a 0 or 180° phase shift is desirable. When the control point at X is connected with ground, the section B of V₁ conducts and the circuit behaves as a grounded grid amplifier giving no phase shift at the plate; however, a positive voltage

5 at control point X sufficient to bias the section B of V₁ to cut off, equal to voltage e_o, would allow the section A to function as a grounded cathode amplifier. The fact that the output plates of both sections of the tube are tied together, as are the grid of V_{1a} and the cathode of V_{1b} which comprise the input, provides the same capacity to the phase correcting circuit to be described infra. The gains of V_{1a} and V_{1b} may be matched by changing cathode resistor R₁ and/or altering the capacity of bypass capacitor C₂. The output from V₁ is applied to the grid of tube V₂ which is a standard amplifier circuit with a tuned plate. The output of V₂, since the device is designed for high frequencies, is tripled by the resonant plate circuit and tube of the final stage V₃. A doubler or quadrupler circuit may be used; however, a tripler allows the 0-180° phase control to be placed at the input. An 832A tube is shown for V₃ although other tubes may be used depending on the frequency and power requirements. The grid coil L₁ of V₃ is wound through the plate coil L₂ of stage V₂ while the plate circuit consists of a 10 pair of brass rods 13, 14 connected to the plates and shorted at approximately $\lambda/8$. A tuning capacitor C₄ across the plate terminals of V₃ provides for a resonance adjustment.

The phase sensing device is null seeking since it must be insensitive to the phase dictated by the control of V₁. The phase sensing device is basically a sum and difference detector which receives the output signal by means of a pickup loop L₃ and the input signal by means of a tripler comprising diodes D₁ and D₂ and a filter network F₁ for 15 removing unwanted harmonics. Assuming the voltage supplied by the pickup loop L₃ to be e₂ and the output from D₁ and D₂ to be e₁. Then the D.C. detected voltage across the diodes D₃ and D₄ of the phase sensing device will be e₁+e₂ and e₁-e₂. The voltage across diode D₃ will be positive while voltage across D₄ will be negative. The detected signals will be equal and opposite in sign and the output voltage from the phase sensor will be 0. This condition occurs when either e₁ or e₂ are zero or when e₁ is 90° out of phase with e₂. 20 A half wave line provides 180° phase reversal for e₂. A $\lambda/4$ line is placed between the V₃ output and the phase sensing device in order that the e₂ voltage will be kept at either 0 or 180° in phase with respect to e₁. Thus a 25 D.C. output signal appears at the grid of the right hand section of V₄ that is proportional to the phase difference and of the same sign is available for operating the phase corrector. For large excursions about zero phase difference the device is not linear, however, the phase corrector is designed such that stable nulls occur only at 30 multiples of 360°.

A conventional D.C. amplifier at V₄ amplifies the signal from the phase sensing portion of the schematic and applies its output voltage e₃ to the correction device which 35 in this case is a reactance tube V₅ capable of providing a phase shift in proportion to its input voltage e₃. V_{5a} acts as a grounded grid amplifier for the signal from V₁ and acts as a conventional amplifier with respect to the control voltage e₃ and has its output applied to pentode section V_{5a}, the reactance tube portion of V₅. The control voltage e₃ and the output signal from V₁, which is shifted

90° out of phase by capacitor C_5 , are applied to V_{5b} with the control signal e_3 adapted to vary the amplification of V_{5b} .

The output of V_{5b} is applied to the control grid of V_{5a} and is out of phase with the plate voltage such that a change in reactance is seen at the input. V_{5a} provides control of the resonant circuit of the amplifier V_1 which comprises L_R , the plate output capacitance of V_1 and the reactance tube V_5 . Thus it can be seen that an error signal proportional to the phase difference between the input and output of an amplifier is used to control a reactance tube which adjusts the resonant circuit capacitance to hold the phase of an amplifier constant and independent of signal amplitude.

The alternative embodiment of Figure 3 is basically the same circuit as Figure 2, with the differences noted below. In the figures like characters designate like parts. In Figure 3, the output of V_1 is applied through an input capacitor C_3 to a phase shifter comprising R_p , R_{imp} and a transformer section, which in this case is suitable for high frequencies and utilizes a section of $\lambda/2$ transmission line in conjunction with a voltage variable capacitor C_6 which may be a back biased silicon diode. The control voltage e_3 is applied to C_6 and changes its capacitance and thus changes the phase between the output voltage to amplifier unit V_{2A} , V_{2B} , V_3 , and the input from V_1 without affecting the relative amplitude of the input and output voltage. V_{2A} and V_{2B} are substitute stages for V_2 of Figure 2 and are standard amplifiers with tuned plates to provide extra gain over that available in the embodiment of Figure 2.

Although the invention has been described with reference to particular embodiments, it will be understood to those skilled in the art that the invention is capable of a variety of alternative embodiments within the spirit and scope of the appended claims. For example, where V_1 is a standard amplifier without a means for phase shifting, the tripler portion of V_2 and V_3 and diodes D_1 and D_2

may be eliminated since the same frequency could appear throughout the device.

I claim:

1. In apparatus for stabilizing the phase of electronically amplified signals, the combination of a first amplifying means having signal input and output circuits, second and third amplifying means having inter-linked inductance coils providing a tunable input to said third amplifying means, said third amplifying means also including dual output electrodes forming with said inter-linked inductance coils a resonant couple, and a tuning capacitor bridging said electrodes, a signal pick-up coil adjacent said resonant couple, a pair of oppositely-poled diodes in parallel circuits connected to said pick-up coil and also to the signal input circuit of said first amplifying means, and means for applying to the signal output circuit of said first amplifying means a phase correction voltage whose amplitude is proportional to the algebraic difference, if any, between the output voltages of said oppositely-poled diodes.
2. Apparatus as defined in claim 1, wherein said correction voltage-applying means includes a reactance tube having a plate circuit connecting with the signal output circuit of said first amplifying means, a first grid circuit including a resonance-controlling inductance unit forming part of the signal output circuit of said first amplifying means, and a second grid circuit receiving the amplified algebraic difference output of said oppositely-poled diodes.
